UNITED STATES PATENT OFFICE.

HARRY V. KEELY, OF BROOKLYN, NEW YORK.

DESIGN FOR A TOY RUNABOUT.

59,898.

Specification for Design.

Patented Dec. 6, 1921.

Application filed July 25, 1921. Serial No. 487,558. Term of patent 7 years.

To all whom it may concern:

Be it known that I, HARRY V. KEELY, a citizen of the United States, residing in New York city, borough of Brooklyn, in the county of Kings and the State of New York, have invented a new, original, and ornamental Design for Toy Runabouts, of which the following is a specification, reference being had to the accompanying drawings,

forming a part thereof, and of which Figure 1 is a side view, Fig. 2 is a front elevation, and Fig. 3 is a rear elevation of a toy runabout showing my new design.

I claim:

The ornamental design for a toy runabout, substantially as shown.

HARRY V. KEELY.
